UNITED STATES PATENT OFFICE.

MILTON L. EDMUND, OF DANBURY, IOWA.

WINDOW.

SPECIFICATION forming part of Letters Patent No. 279,364, dated June 12, 1883.

Application filed October 16, 1882. (No model.)

To all whom it may concern:

Be it known that I, MILTON L. EDMUND, of Danbury, in the county of Woodbury and State of Iowa, have invented a new and useful 5 Improvement in Windows, of which the following is a full, clear, and exact description.

The invention consists in an improvement of the means employed for the escape of flies and other insects, as well as for ventilation, without hoisting windows, as hereinafter described.

Reference is to be had to the accompanying drawings, forming part of this specification, in which similar letters of reference indicate corresponding parts in all the figures.

Figure 1 is a front elevation of part of a window constructed according to my invention. Fig. 2 is a section of the same, taken on the line *x x* of Fig. 1. Figs. 3 and 4 are details of the apparatus in section.

Over any one or all of the panes, *a*, of a window I propose to arrange a valve, *b*, preferably of circular form, but which may be of other form, to open a passage, *c*, over the pane, as represented in the upper part of Fig. 2, or 25 close it, as shown in the lower part of said figure, the objects being to provide for the escape of the flies and for ventilation, as above described.

In carrying out my invention I prefer to employ roller-valves *b*, having a groove, *d*, along one side, and mounted on pivots *e*, so that, being turned by a screw, *f*, and teeth *g*, the screw having a thumb-bit, *h*, projecting out of the inclosing-case for the roller, it may be 30 readily shifted for opening or closing the passages. The said case consists of the front plate, *i*, and back plate, *j*, connected together by bars *k*, and attached to the under side of the rail or bar *l* of the window-sash, with plates *m* connected to them at the ends for the pivots of the rollers, and containing a notch, *n*, in the lower end to receive the upper edge of the panes for supporting them thereat. The connecting-bars *k* for the two plates of the case are attached 40 to them below their upper edges, in order that they may overlap the lower edges of the sash-

50 rails *l*, and be fastened thereto by screws *o*, the rails being rabbeted to let the plates in flush with the sides of the rails. The inside plate, *i*, is curved inward at the lower edge toward the glass for a finish. The rollers will fit snugly between the side plates of these inclosing-cases, and the shape of the groove may be such as to fit well against the upper edges of the panes for effectually closing against the weather.

55 I am aware that it is not new to provide a valved or dampered outlet at the top of a window-screen; but

What I do claim as new and of my invention is—

60 1. As an improvement in valves or dampers over window panes or screens, a roller-valve, *b*, having the groove *d*, and arranged on pivots *e* in a receptacle of the sash-frame, as and for the purpose specified.

65 2. The front and back plates, *i j*, connected by bars *k*, in combination with the rabbeted sash-bar *l*, overlapped by bars *i j*, the screws *o*, and the bearing-plates *m*, notched at *n*, whereby a valve may be supported between the sash-frame and one or more panes, as described.

70 3. The combination of the grooved roller-valves *b*, inclosing-plates *i* and *j*, and means for operating said roller-valves, with a window, substantially as described.

75 4. The combination of inclosing-plates *i j*, roller-valves *b*, and end plates, *m*, with the panes *a* and rails *l* of a window, substantially as described.

80 5. The inclosing-plates *i j*, connected together by bars *k* and end plates, *m*, and connected to the rails *l* of the window, substantially as described.

85 6. The pivot-supporting end plates, *m*, having notch *n*, in combination with roller-valves *b* and the window-panes *a*, substantially as described.

MILTON L. EDMUND.
